COMBINED LETTER OPENER, ERASER, AND BRUSH

Alfred T. Le Beau, Oakland, Calif.

Application October 7, 1955, Serial No. 38,288

Term of patent 14 years

(Cl. D74—1)

FIG. 1

FIG. 2

FIG. 4

Fig. 1 is an enlarged front elevational view of the combined letter opener, eraser, and brush comprising the design of the present invention;

Fig. 2 is a right side elevational view as seen from the right of Fig. 1;

Fig. 3 is a rear elevational view thereof; and

Fig. 4 is a left side elevational view thereof as seen from the left side of Fig. 1.

I claim:

The ornamental design for a combined letter opener, eraser, and brush, substantially as shown.
